UNITED STATES PATENT OFFICE

AUGUST KADOW, OF TOLEDO, OHIO, ASSIGNOR, BY DIRECT AND MESNE ASSIGNMENTS,
TO THE VACUUM CASTING COMPANY, OF TOLEDO, OHIO, A CORPORATION OF OHIO

MEANS AND METHOD FOR FILLING MOLDS WITH MOLTEN METAL

Application filed March 15, 1926. Serial No. 94,716.

My invention relates to means and method of filling a mold with molten metal, and has for its object to completely fill a mold with molten metal under pressure while avoiding danger of blow holes.

When metal is forced into a mold under considerable pressure the entering jets of metal frequently set up eddy-currents and cause the metal to solidify around air pockets, leaving blow holes in the casting. When metal is forced in under pressure higher than atmospheric, it is evident that such eddy-currents readily trap air in the casting. When the mold cavity is evacuated and metal is forced in by atmospheric pressure, there is comparatively little air in the mold cavity to be entrapped, but in spite of this fact it is found that the metal is apt to set around cavities where it spurts into the mold.

When the metal is introduced into the mold under lower pressure, so that no jets are formed, there is danger of the metal setting before it flows into all of the remote portions of the mold cavity. This is particularly true when the cast article has projections of considerable length in proportion to their diameter.

In order to avoid both of these difficulties I reduce the initial speed of flow into the mold cavity, so as to avoid spouting the metal into the mold in jets, and at the same time I provide for the final filling of the mold under comparatively high pressure.

This object may be accomplished in several different ways. It is possible to fill the mold by means of an initial low vacuum and final high vacuum, or by an initial low pressure upon the entering metal with increasing pressure as the mold filled; but the mold is filled so quickly in ordinary operation that controlling the entrance of the metal by controlling the degree of vacuum within the mold cavity or by controlling the pressure upon the metal presents great difficulties, and therefore I prefer to accomplish my object by a modification of the inlet opening or openings along the lines which will now be described.

In the accompanying drawings, forming a part of this specification, Figure 1 is an elevation of the inside of one-half of a mold

embodying one form of my invention; Figs. 2 and 3 are enlarged sections along lines 2—2 and 3—3 respectively on Fig. 1; Fig. 4 is a partial elevation similar to Fig. 1 showing a modified form of mold inlet; Fig. 5 is a section on the line 5—5 of Fig. 4; Fig. 6 is an enlargement of a portion of Fig. 4, and Figs. 7 and 8 are sections on the lines 7—7 and 8—8, respectively, Fig. 6.

In the construction shown in Fig. 1 there is shown a mold-half 10, which is adapted to cooperate with a similar mold-half in a well known manner to form a mold cavity. As the two halves are, or may be, constructed the same, it is necessary to describe but one of the halves.

The mold is constructed with a cavity 11 in which the desired casting is formed. Grooves 12—12 in the mold face lead to a suitable outlet 13 connecting to any suitable means for exhausting the air from the mold. The partitions 14 between the passages 12 and mold cavity 11 may be left flush with the rest of the mold wall, and still air will pass from cavity 11 to passages 12 more readily than from the exterior of the mold into said passages, because the passages are nearer to the mold cavity than to the exterior of the mold. However, I prefer to grind away partitions 14 slightly, so as to facilitate the passage of air from cavity 11 to passages 12, but not enough to allow the passage of molten metal.

In the form of mold shown in Fig. 1 there is an inlet opening 15 leading into a reservoir 16, from which a plurality of openings 17 lead into the mold cavity 11. As will be readily seen from a comparison of Figs. 2 and 3, the total cross-section of passages 17 is considerably in excess of the cross-section of passage 15; also the mold is not cut away at 18 directly opposite the entrance 15, so that this portion 18 forms a baffle to intercept the stream of metal entering through inlet 15 and prevent its spouting directly into the mold.

It will be readily understood that in operation, when the lower end of the mold is dipped into a bath of molten metal and mold cavity 11 is evacuated, atmospheric pressure 100

forces the molten metal through inlet 15 and against baffle 18, whence it spreads out in both directions to fill reservoir 16. After reservoir 16 is filled the metal rises through openings 17 and fills mold cavity 11. Since the cross-section of passages 17 is materially greater than the cross-section of passage 15, the flow of metal through passages 17 into the mold will be at considerably less velocity than the flow of metal through passage 15, and in this way the tendency of the metal to enter the mold in jets which form blow holes is avoided. At the same time it will be clear that, if the metal should become somewhat stiff before the upper portion 19 of mold cavity 11 becomes completely filled, the entire differential pressure between atmospheric pressure and the degree of vacuum contained in the mold would be exerted upon the metal to complete the filling of this portion of the mold.

While this structure is shown and described as applied to a mold intended to be filled by the suction method, it will be clear that the same result in controlling the flow of metal into the mold would be achieved if metal were forced through inlet 15 under pressure other than or greater than atmospheric.

In the form of inlet shown in Fig. 4, a similar effect upon the flow of metal into the mold is achieved by a somewhat different structure. In this form there is shown a mold similar to that shown in Fig. 1, and having like parts indicated by the same reference numbers with the addition of the letter *a*, the difference between the two molds being in the construction of the inlet openings. In the form shown in Fig. 4 there are a plurality of inlet openings 20. Interposed between each pair of inlets 20 there is a partition 21. The upper ends of passages 20 are made considerably wider than the lower ends and the intervening partitions 21 are preferably of stream line formation, their lower ends being at the widest point in the formation.

Interposed in the center of each passage 20, immediately above the inlet opening, is a baffle or stream-divided 22. These baffles 22 are also preferably of stream line formation, but in this case the entire formation is completed. In this way the metal entering through a passage 20 is divided into two channels each of which gradually increases in breadth. By constructing the passages in this manner there is little tendency for the metal to flow through any portion of a given cross section of the passage at a greater velocity than through other portions of said cross section, and as the width of the passage is gradually increased from the inlet end to the mold cavity, it will be readily seen that the velocity of the entering metal is correspondingly reduced.

The form of inlet shown in Fig. 4 is ad-

vantageous in providing a more direct entrance into the mold with less metal in the gate than in the form shown in Fig. 1, but the inlet shown in Fig. 4 requires greater care and exactness in formation, and, therefore, increases the first cost of the mold.

It will be evident that the form of gate shown in Fig. 4 is equally well adapted for filling a suction mold or filling a mold where the metal is introduced under pressure other than atmospheric.

In both instances the metal has been shown entering the mold cavity from the bottom. Some of the advantages of my invention could be realized where the metal is introduced into the upper portion of the mold through gravity or otherwise, but where so introduced there is always a tendency for the metal to form into streams which flow through the mold cavity to its bottom and result in a certain amount of spraying and splashing of the metal with resultant danger of blow holes. Therefore, I prefer to introduce the metal at the bottom or at the substantially lowest point in the mold cavity. When so introduced and properly controlled the metal flows into the mold gradually and no jets are created within the mold cavity.

I have shown two forms of mold inlets, both of which are well adapted for use with suction molds and for use with narrow inlet slots, such as described and claimed in my co-pending application Serial No. 94,712 for Process and apparatus for casting liquid molten metal, now Patent No. 1,606,236.

It will be readily understood that other forms of inlet openings may be devised, both where narrow inlet slots are used and where inlet openings of other shapes are formed, without departing from the spirit of my invention.

It will be clear also that, when using a mold with an inlet similar to that shown in Fig. 1 and wherein a reservoir like reservoir 16 is provided, the inlets 17 may be made narrow enough to prevent the escape of metal by gravity, while inlet 15 may be made substantially circular, if desired, and large enough so that the molten metal remaining in reservoir 16 will flow back out through inlet 15 when the mold is lifted from the bath.

The effect of inlets of the form shown in Figs. 1 and 4 is to baffle the entering jets of molten metal and to reduce the pressure and the velocity with which they enter the mold cavity until the cavity is nearly filled, but when any resistance is offered to the further entrance of molten metal, the full pressure of the metal at the initial or outside opening is available to overcome this resistance and completely fill the mold. Therefore, these inlets have the effect of automatically governing the pressure so that the main part of the

mold cavity is filled at low pressure, while the final filling is done at high pressure.

It will be seen therefore, that the velocity of the metal first entering the mold is sufficiently reduced to avoid blow holes caused by spouting jets, and at the same time the maximum pressure available for completely filling comparatively long and narrow mold cavities, or projections from the main cavity, is not reduced. By the structure of the inlet, the benefits of both low pressure and high pressure are obtained without the drawbacks incident to the use of either alone.

Various other modifications may be made 15 within the scope of my invention, which is defined in the appended claims.

What I claim is:

1. The process of casting metal, which consists in withdrawing air from a mold cavity, 20 introducing molten metal into the lower portion of the cavity under comparatively low differential pressure, continuing to withdraw gas from the cavity until it is completely filled and increasing, during the filling process, the differential between the pressure of gases on the surface of the metal rising in the cavity and the fluid pressure forcing metal into the cavity.

2. The process of casting metal, which consists in introducing molten metal into a mold cavity at the lower portion thereof, governing 30 the velocity of the metal first entering the cavity so that jets will not be formed, and completing the filling of the cavity under comparatively high pressure.

3. The process of casting metal, which consists in passing metal upward from a molten bath thereof into the lower portion of a mold cavity in a stream increasing in cross-section 40 as it approaches the mold cavity.

4. The process of casting metal, which comprises forcing the metal upward from a molten bath thereof under comparatively high pressure, intercepting the metal passing 45 from the bath and changing its direction while increasing the cross-section of the flowing metal, and introducing the metal into the bottom of the mold cavity in such increased cross-section.

5. In apparatus for casting metal, a mold having an inlet opening in its bottom, the cross-section of said opening being materially greater where it joins the mold cavity than at the exterior surface of the mold.

55 6. In apparatus for casting metal, a mold having an inlet opening in its bottom, the cross-section of said opening being materially greater where it joins the mold cavity than at the exterior surface of the mold, the said 60 inlet opening being so constructed as to prevent a jet of metal from traveling in a rectilinear path from the exterior of the mold into the mold cavity.

7. A mold provided with a mold cavity 65 having an inlet into its lower portion, said

inlet being of such dimension in one direction as to prevent the passage therethrough of molten metal from the mold cavity by gravity, a reservoir with which said inlet connects said mold cavity, and a sprue opening from the exterior of the mold into said reservoir, said sprue opening being large enough in all cross-sectional dimensions to allow molten metal to flow out therethrough from said reservoir by gravity.

8. A mold provided with a mold cavity having an inlet into its lower portion, said inlet being of such dimension in one direction as to prevent the passage therethrough of molten metal from the mold cavity by gravity, a reservoir with which said inlet connects said mold cavity, and a sprue opening from the exterior of the mold into said reservoir, said sprue opening being large enough in all cross-sectional dimensions to allow molten metal to flow out therethrough from said reservoir by gravity, and the total cross-sectional area of said sprue opening being materially less than that of the connection between the reservoir and mold cavity.

In testimony whereof, I have hereunto signed my name to this specification.

AUGUST KADOW.
